UNITED STATES PATENT OFFICE

JOSEPH EIFEL, OF CHICAGO, ILLINOIS

LOOSE-SHEET HOLDER

Application filed December 17, 1921. Serial No. 523,082.

The present invention relates to paper files, binders and the like. Among the primary objects of the invention are to improve the class of paper files and the like generally, including a base member having projecting pins or posts thereon for receiving the sheets of paper. The present improvement includes a novel arrangement of filing posts which are relatively reciprocally movable, and the planes of movement of which are coincidental to each other, together with the mechanism for so moving the filing posts that their respective ends abut and afford a smooth joint when closed; to provide a device of the character outlined above, which includes a minimum number of moving parts, is simple and compact and is a complete unit itself; to provide a device embodying the improved principle of operation and structural arrangement set forth herein which may be quickly installed as a unit, may be manufactured at low cost, is durable and is capable of quick and facile manipulation, together with such further and additional objects as may hereinafter appear or be pointed out.

In attaining the objects suggested as well as certain further benefits and advantages to be below disclosed, I have provided a construction, one embodiment of which is illustrated in the accompanying drawings in which:—

Figure 1 is a top plan of a preferred form of the device of my invention in closed position;

Figure 2 is a similar view of the device in open position;

Figure 3 is a side elevation, certain parts thereof being broken away;

Figure 4 is a transverse section taken on the line 4—4 of Figure 1, looking in the direction of the arrows, certain parts thereof being broken away;

Figure 5 is a longitudinal section taken on the line 5—5 of Figure 1, looking in the direction of the arrows, certain parts being broken away;

Figure 6 is a similar view taken on the line 6—6 of Figure 1, looking in the direction of the arrows; and

Figure 7 is a fragmental elevational view looking from the right-hand side of Figure 1.

The invention in preferred form includes, with a suitable base member, a pair of supporting plates mounted on said base substantially in a common horizontal plane for relative movement and carrying the filing posts, a so-called lazy-tongs element connecting the plates, one of the latter being fixedly secured to the base member; suitable locking means being associated with the lazy-tongs mechanism for retaining the posts in open or closed positions. In the embodiment of the invention disclosed in the drawings, described in detail later, an expansion spring is provided for separating the plates laterally, to open the device, but it will be observed that the functioning of the spring may be reversed, if desired, without departing from the spirit of the invention.

Referring to Figures 1 and 2 of the drawings, I employ conveniently a rectangular base-board, 10, which is of a suitable form, and shape, that is, length and width depending on the purpose contemplated and size desired, the device of my invention being generally placed at, or near, one end, as shown. In the preferred embodiment, a substantially rectangular plate, 11, is fixedly secured by screws, 12, to the board, this fixed plate having a movable plate, 13, connected thereto through a lazy-tongs element, generally designated at 14.

The contiguous side margins of the plates 11 and 13 may be offset, as at 15 and 16, respectively, to provide marginal flanges 17 and 18, respectively, raised from the board, 10, and providing bearings for the lazy-tongs, and for an additional purpose which will presently appear.

A pair of spaced upstanding posts, 19—19, preferably hollow, are carried by the plate 11, the lower ends of the posts passing through the said plate and being swaged as at 20 (Figure 6), into engagement with the underside thereof. The upper ends of the posts 19—19 are bent toward the horizontal in the direction of the plate 13, as at 21—21, to provide sockets 22—22.

The plate 13 carries spaced posts 23—23,

complemental to the posts 19—19, and curved toward the latter. The posts 23—23 terminate with straight horizontal portions 24—24, pins 25—25 being threaded into said portions 24—24. The outer projecting ends of the pins 25—25 are semi-spherical and are adapted to seat in the sockets 22—22 when the filing device is closed (Figure 3). Thus, when closed, the joint between the posts 19—19 and 23—23 is practically continuous with no projecting corners. Thus, a substantially continuously curved portion is provided disposed toward the posts 21, so as to facilitate manipulation of papers held thereby. The lower ends of the posts 23—23 pass through the plate 13 and are swaged at 26 (Figure 6) into engagement with the underside thereof.

The plate 13 is slideable upon the exposed surface of the board 10, and as the plate 11 is on the same surface, it follows that the posts 19—19 and 23—23, move rectilinearly relatively to each other in coincident planes.

The lazy-tongs 14 comprises, preferably 25 links 27 and 28, pivotally connected at their medial portions by a pin 29. The medial portions 30 and 31 are disk-like in shape and have relatively offset radial arms 32, 33 and 34 and 35, respectively, extending therefrom, 30 said arms having their respective outer margins substantially tangential to the peripheral margins of the medial portions.

The free ends of the arms 33 and 35 are pivotally connected to the top surface of the flanges 17 and 18, by means of rivets 36 and 37, respectively, while the free ends of the arms 32 and 34 are pivotally and slidably connected by means of rivets 38 and 39 to the flanges 17 and 18, respectively. Slots 40—40 40 are provided in the flanges 17 and 18 to permit of such a pivotal sliding connection.

The pin 29 is provided with a smooth shank and a reduced threaded under portion 29' receiving a nut 41 having a grooved periphery 45 receiving the loop 42 of an expansion spring having divergent arms 43 and 44 which bear, respectively, upon the shoulders formed by offsetting the plates 11 and 12, thus tending to separate the plates.

50 As will be seen from Figures 4 and 5, the smooth shank projects beyond the under disk portion and receives a spacing washer 45, disposed between the nut 41' and said disk portion.

55 The slots 40—40 insure that the plate 13 will, throughout its movement, be parallel to the plate 11, so that when the plates are brought into proximity the pins 25 will accurately engage in their respective sockets.

60 As is perhaps best shown in Figure 2, the margin of the flanges 17 and 18 are provided with complemental semicircular recesses 46—46 embracing the pin 29 and washer 45 when the device is closed.

65 The locking means preferably comprises an

angular lever 47 having its shorter portion 48 pivoted at its end at 49 on the arm 34, the longer portion 50 of said lever extending transversely and from one side of the filing device, a suitable knob 51 being carried by said arm 50 and serving as a handle. A curved plate 52 is mounted rigidly on the arm 32 by rivets 53, the curvature of the plate being described from the axis of the pin 29.

70 Detents 54 and 55 project from the outer edge of the plate 52, and engage in a recess 56 in the lever 47 near the junction of the portions thereof, and the edge of the lever adjacent each side of said notch is inclined as at 57, the lever riding on these edges against and into engagement with one or the other detent.

75 The flange 17 is extended at 58 and provided with an upstanding leg 59 to which is riveted a flat spring 60 bearing against the inner margin of the portion 50 of said lever.

80 The operation of the present device embodying my invention is as follows:

85 Assuming the device to be open, the paper properly punched is placed over the posts 19. To close the device, pressure is applied to the lever 50 against the tension of the spring 60 and the device is unlocked. One pair of the posts 19 and 23 are then grasped between the forefinger and thumb of one hand and pressure applied, thus moving the plate 13 and posts 23—23 toward the plate 11 and complemental posts 19—19, until said posts engage, whereupon the detent 54 engages the notch 56 and the device is locked closed. It will be observed that the plates moving in the same horizontal plane insure that the posts will be displaced in a path parallel to said plane of movement. While a preferred embodiment of my invention has been described, 90 I reserve the right to modify the structure where necessary for the sake of mechanical refinement without departing from the essence of the invention and scope of the claims.

95 To open the device, pressure is applied to the arm 50 and the detent 54 is thus disengaged from the notch 56. This procedure releases the plate 13, and under the tension of the spring arms 43 said plate is moved outwardly and the device is opened. When the limit of outer movement is reached the plate 13 is locked by the detent 54 engaging the notch 56.

100 Having thus described my invention and illustrated its use, what I claim as new and desire to secure by Letters Patent is:—

1. In combination, a base member, a pair of relatively movable plates on said base member, complemental separable filing members on said plates, and means operatively connecting said plates for automatically moving one of said plates away from the other plates on said base member.

125 2. In combination, a base member, a pair of relatively movable plates on said base mem-

ber, complemental separable filing members on said plates, means for automatically moving one of said plates on said base member to open said filing members, and locking means associated therewith for holding said plates in the extreme limits of relative movement.

3. In combination, a base member, a pair of relatively movable plates on said base member, complemental separable filing members on said plates, means for automatically moving one of said plates on said base member to open or close said filing members, and means for automatically locking said movable plate in the extreme limits of its movement.

4. In combination, a base member, a pair of relatively movable plates on said base member, complemental separable filing members on said plates, one of said plates being manually movable to close them, and means operatively connecting both plates for automatically moving said movable plate in the opposite direction.

25 5. In a filing device, complemental pairs of separable filing members, a base member on which said filing members are mounted, said latter members being manually movable toward each other, means for automatically moving said members away from each other, and locking means associated therewith for locking said plates in both of their relative limits of movement.

35 6. In a filing device, complemental pairs of separable filing members, a base member on which said filing members are mounted, said filing members being manually movable in one direction, means for automatically moving said filing members relatively in another direction, and means for locking said filing members in their connected or separated positions.

45 7. In a filing device, separable opposed filing members arranged in a common plane and means for relatively moving said members in said common plane in one direction including a lazy-tong element.

55 8. In a filing device, separable opposed filing members arranged in a common plane, means for automatically relatively moving said members in said common plane in one direction, and spring-actuated means for locking said members at the limits of relative movement thereof.

55 9. In a filing device, separable opposed filing members arranged in a common plane, spring-actuated means for relatively moving said members in said common plane in one direction, and means for locking said members at the limits of relative movement thereof.

60 10. In a filing device, separable opposed filing members arranged in a common plane, spring-actuated means for relatively moving said members in said common plane in one direction, and spring-actuated means for

locking said members at the limits of relative movement thereof.

11. In combination, a base member, a plate fixedly mounted on said base member, a second plate movable on said base board in a plane coincident with said fixed plate, a lazy-tong element connecting said plates, filing posts in said plates, and means for locking said second plate in the limits of movement thereof.

75 12. In combination, a base member, a plate fixedly mounted on said base member, a second plate movable on said base member in a plane coincident with said fixed plate, a lazy-tong element connecting said plates, complemental posts on said plates adapted to abut and connect, and means for locking said movable plate in the limits of movement thereof.

80 13. In combination, a base member, a plate fixedly mounted on said base member, a second plate movable on said base member in a plane coincident with said fixed plate, a lazy-tong element connecting said plates, filing posts in said plates, and means on said lazy-tong element for locking the same and said plates.

85 14. In combination, a base member, a plate fixedly mounted on the surface of said base member, a second plate movable on said base member, a projecting post carried by one of said plates, a curved post carried by the other plate and complemental to the first-mentioned post, one of said posts terminating in a curved socket and abutting the end of the other post, and a pin on the extremity of the other of said posts for engagement in said curved socket whereby to provide a substantially continuous curved portion adjacent to the joint.

95 15. In combination, a base member, a plate fixedly mounted on the surface of said base member, a second plate movable on said base member, a pair of projecting posts carried by one of said plates, complemental curved posts carried by the other plate, one of said posts terminating in sockets, pins on the extremities of the other of said posts for engaging in said sockets, spring means tending to maintain said plates in a predetermined position, and locking means for said plates.

100 16. In combination, a base member, a plate fixedly mounted on the surface of said base member, a second plate movable on said base member, a pair of projecting posts carried by one of said plates, complemental curved posts carried by the other plate, lazy-tongs connecting said plates and comprising links pivotally connected at their medial portions affording arms, and locking means for said arms.

115 17. In combination, a base member, a plate fixedly mounted on the surface of said base member, a second plate movable on said base member, a pair of projecting posts carried by one of said plates, complemental curved posts carried by the other plate, flanges on the

adjacent margins of said plates, lazy-tongs comprising links pivotally connected at their medial portions to provide arms, which in turn are pivoted on said flanges, and locking means for two adjacent arms of said lazy-tongs.

18. In combination, a base member, a plate fixedly mounted on the surface of said base-board, a second plate movable on said base member, a pair of projecting posts carried by the other plate, flanges on the adjacent margins of said plates, lazy-tongs comprising links pivotally connected at their medial portions to provide arms, which in turn are pivoted on said flanges, sockets and pins on said posts, means for separating said plates, and locking means on said lazy-tongs element.

19. In combination, a base member, a pair of plates thereon having their longitudinal axes parallel, one being secured thereon and the other movable, means arranged between and for connecting said plates and maintaining the same with their longitudinal axes parallel throughout their relative movement, and complemental filing posts carried on said plates and adapted for connection and disconnection.

20. In combination, a base member, a pair of plates thereon having their longitudinal axes parallel, one being secured thereon and the other movable, means connecting said plates and maintaining the same with their longitudinal axes parallel throughout their relative movement, complemental filing posts carried on said plates, and means cooperating with said connecting means for automatically locking said plates at the limits of relative movement thereof.

21. In combination, a base member, a pair of plates thereon having their longitudinal axes parallel, one being secured thereon and the other movable, means for connecting said plates and maintaining the same with their longitudinal axes parallel throughout their relative movement, complemental filing posts carried by said plates, and spring means between the plates tending to force the same apart.

22. In combination, a base member, a pair of plates thereon having their longitudinal axes parallel, one being secured thereon and the other movable, means connecting said plates and maintaining the same with their longitudinal axes parallel throughout their relative movement, complemental filing posts carried on said plates, and means for automatically locking said plates at the limits of relative movement thereof.

In testimony whereof I have hereunto signed my name.

JOSEPH EIFEL.
